UNITED STATES PATENT OFFICE

OSCAR G. JOSEPH, OF LOUISVILLE, KENTUCKY

WINDOW-CONTROL DEVICE

Application filed July 10, 1929. Serial No. 377,239.

This invention is a device for effecting the closing of an open window.

One of the objects of the invention is to provide a manually movable window sash with means normally tending to move it to closed position, in association with other releasable means to retain the sash in an open position against its normal closing tendency. A further object is to provide means by which the operation of the sash retaining means may be controlled at a position distant from the window. A further object is to provide an attachment of the character described which may be applied either to an upper or a lower sash.

The invention will be hereinafter fully set forth and particularly pointed out in the claims.

In the accompanying drawing:

20 Figure 1 is an elevation illustrating a typical window-frame stile with the invention applied thereto. Figure 2 is an elevation opposite to that of Figure 1. Figure 3 is a sectional view on the line 3—3 of Figure 1. 25 Figure 4 is a sectional view on the line 4—4 of Figure 1. Figures 5 and 6 are views illustrating a slight modification.

Referring to the drawing, 10 designates a typical stile of a standard window frame, 30 and 11 is the pulley casing which is normally inserted into a recess of the stile. A sash pulley 12, around which the usual sash cord 13 travels, is rotatably mounted upon a shaft 14, which is also rotatably supported within the casing in suitable manner. The sash S is of typical construction and the same is true of the sash weights W.

40 Fixedly mounted on the shaft 14 is a ratchet wheel 15, which is provided with peripheral teeth shaped to be engaged by a spring-pressed pawl 16, pivotally mounted on one side of the pulley 12. Rotatably mounted in the casing 10 is a counter shaft C, having a 45 brake drum 16^a fixedly secured thereto at one end, the other end of said shaft being geared with the shaft 14 in suitable manner. For purposes of illustration the counter shaft is provided with a worm 17, which meshes with a worm gear 18 fixedly mounted on the 50 shaft 14.

The brake drum 16^a is held against rotation by means of a brake lever 19, pivotally supported at one end as indicated at 20, and having a curved surface conforming to the peripheral contour of said drum. Said brake lever is normally held in engagement with the drum by means of a spring 21. The free end of the lever 19 is provided with an eye 22, to which is connected one end of a cord 23, which may be led to any desired convenient operating position. Located beneath the brake lever 19 is an electro-magnet 24, so positioned that said brake lever operates as an armature therefor. The wires from said magnet may be moved to any desired or convenient operating position, and connected with a push button and a source of electricity, which are so well understood in the electrical art that illustration is considered unnecessary.

The structure thus far described is designed for the operation of the lower sash S of a window. In practice, the sash cord pulley is free to rotate as the window is raised, the weight of the usual sash weights W being diminished in any desired way so that the sash slightly overbalances the weights. By means of this arrangement, the pulley 12 is free to rotate as the window sash is raised, the pawl 16 riding over the teeth 55 of the ratchet wheel 15. Just as soon as the sash is released by the person who is moving it to open position, the tendency to reversely rotate the pulley due to the overbalancing effect of the sash, causes the pawl to engage the nearest tooth of the ratchet wheel 15, and closing movement of the sash is resisted by reason of the engagement of said pawl and ratchet, the engagement of the worm shaft 17 with the worm gear 18, and the engagement 60 of the brake lever 19 with the brake drum 16^a. The friction of the brake lever against the surface of the brake drum, together with the angular relation of the teeth of the worm gear and the worm shaft are sufficient to 65 positively lock the pulley 12 against reverse rotation. When it is desired to close the window, the operator either pulls upon the cord 23 or closes the circuit to the magnet 24, as the case may be, whereupon the brake 70

lever 19 is drawn out of engagement with the brake drum 16^a, against the tension of spring 21. As long as the pull upon the cord 25 is maintained, or the circuit through the magnet 24 is maintained, as the case may be, the window sash will gradually lower, it being understood that the pitch of the intermeshing teeth of the worm gearing is such as to retard the closing movement of the sash, so that it will slowly move to closed position without slamming. The reaction of the worm gearing also serves to reduce the required amount of pressure on the brake drum to prevent the sash from closing.

15 The form illustrated in Figures 5 and 6 is designed to be applied to the sash cord pulley of an upper sash, and differs from the figures previously described only in placing the parts in a reversed position, so that the 20 upper sash may be lowered and will be moved to closed position by the increased overbalancing weight of the sash weights. In other words, for the lower sash it is necessary that the sash be slightly heavier than the sash 25 weights, but where the device is applied to the upper sash it is necessary for the sash to be somewhat lighter than the sash weight.

Referring to Figures 5 and 6 it will be observed that the teeth of the ratchet wheel 15^a are disposed oppositely to those of the ratchet wheel 15. The worm 17^a is formed on or attached to the pulley shaft 14, and the worm gear 18^a is carried by the countershaft C. It is obvious that this arrangement is the reverse of that illustrated in the other figures, and that for the movement in the opposite direction, the operation is the same.

It is preferred to establish this differential in load by substituting for the usual sash 40 weights lighter or heavier ones, according to whether they are applied to the lower or the upper sash. The invention is not limited to this arrangement, however, and contemplates the employment of any differential loading 45 means within the scope of the appended claims.

The advantages of the invention will be readily apparent to those skilled in the art to which it belongs. It will be particularly observed that simple means have been provided which will permit of the manual opening of a window sash and insure retention of said sash in the desired open position. An important advantage is that the control device is of such a character that the closing movement of the sash may be arrested at any position within its limits of travel, by permitting the brake lever to reengage the brake drum. Another obvious advantage is that the device may be applied to windows of typical construction now in general use without substantial change of structure.

Having thus explained the nature of the invention and described an operative manner 65 of constructing and using the same, although

without attempting to set forth all of the forms in which it may be made, or all of the forms of its use, what is claimed is:—

1. A window control device of the character described comprising a rotatably supported shaft, a sash cord pulley rotatably mounted on said shaft, means for normally preventing relative rotation of said shaft and said pulley in one direction, and releasable control means normally preventing rotation of said shaft. 75

2. A window control device of the character described comprising a rotatably supported shaft, a sash cord pulley rotatably mounted on said shaft, means for normally preventing relative rotation of said shaft and said pulley in one direction, brake means normally preventing rotation of said shaft, and means controlling the operation of said 80 brake means. 85

3. A window control device of the character described comprising a rotatably supported shaft, a sash cord pulley rotatably mounted on said shaft, means for normally preventing relative rotation of said shaft and said pulley in one direction, a rotatably mounted brake drum operatively connected with said shaft, a brake lever normally engaging said brake drum so as to prevent rotation of said shaft, and control means for 90 said brake lever. 95

4. A window control device of the character described comprising a rotatable shaft, a sash cord pulley rotatably mounted on said shaft, an overthrow clutch device connecting said shaft and said pulley so as to cause them to rotate in unison in one direction, means normally preventing rotation of said shaft in either direction, and control means for releasing the shaft from said rotation preventing 100 means. 105

5. A window control device of the character described comprising a rotatable shaft, a sash cord pulley rotatably mounted on said shaft, an overthrow clutch device connecting said shaft and said pulley so as to cause them to rotate in unison in one direction, a rotatably mounted brake drum, means connecting said brake drum and said shaft so as to prevent rotation of the shaft in either direction, and a brake member releasably 110 engaging said drum. 115

6. A window control device of the character described comprising a rotatable main shaft, a sash cord pulley rotatably mounted on said shaft, an overthrow clutch device connecting said shaft and said pulley so as to cause them to rotate in unison in window-closing direction, a worm gear fixed to said shaft, a worm shaft engaging said gear, 120 means normally preventing rotation of said worm shaft so that the window-closing rotation of the main shaft is prevented, and control means for releasing said worm shaft from said rotation prevention means. 125 130

7. A window control device comprising a rotatable shaft, a sash cord pulley rotatably mounted on said shaft, an overthrow clutch device connecting said shaft and said pulley so as to cause them to rotate in unison in one direction, a brake drum, gearing connecting said brake drum and said shaft, and a movably mounted brake member releasably engaging said drum so as to free the first mentioned shaft for rotation with said pulley.

10. A window control device of the character described comprising a rotatable shaft, a sash cord pulley rotatably mounted on said shaft, an overthrow clutch device connecting said shaft and said pulley so as to cause them to rotate in unison in one direction, a brake shaft, a brake drum on said shaft, a worm on said brake shaft, a worm gear on the pulley shaft in mesh with said worm shaft, and a brake member releasably engaging said brake drum so as to free said pulley shaft for rotation with said pulley.

15. A window control device of the character described comprising a rotatable shaft, a sash cord pulley rotatably mounted on said shaft, an overthrow clutch device connecting said shaft and said pulley so as to cause them to rotate in unison in one direction, a brake drum, a brake lever, a spring yieldably holding said lever in engagement with said brake drum, connections between said brake drum and said pulley shaft to normally prevent rotation of said shaft and pulley in the one direction mentioned, and means for holding said brake lever against the tension of said spring.

20. A window control device comprising a rotatable shaft, a sash cord pulley rotatably mounted on said shaft, a ratchet wheel fixed to said shaft, a pawl mounted on said pulley so as to engage said ratchet wheel, a brake drum, means releasably holding said brake drum against rotation, means connecting said brake drum and said pulley shaft so as to prevent rotation of said shaft in one direction, and control means for maintaining said brake drum and its holding means in disengaged relation.

25. A window control device comprising a rotatable shaft, a sash cord pulley rotatably mounted on said shaft, a ratchet wheel fixed to said shaft, a pawl mounted on said pulley so as to engage said ratchet wheel, a counter shaft, a brake drum secured to the counter shaft, gear mechanism connecting said counter shaft with the first mentioned shaft so as to prevent rotation of said shaft in one direction, and control means for maintaining said brake drum and its holding means in disengaged relation.

30. The combination with a window sash and a weight therefor, there being a differential in the load of the sash and the weight so as to cause the sash to normally move to closed position, of a rotatably mounted shaft,

a sash cord pulley rotatably mounted on said shaft, means for causing said shaft and pulley to rotate together in one direction, a sash cord passed around said pulley and connecting said sash and said weight, means for preventing rotation of said pulley and said shaft in the one direction mentioned so as to support said sash in open position, and control means for releasing said pulley from said rotation preventing means.

35. In testimony whereof I have hereunto set my hand.

OSCAR G. JOSEPH.
